US00D961329S

(12) **United States Design Patent** (10) **Patent No.:** **US D961,329 S**
(45) **Date of Patent:** **** Aug. 23, 2022**

(54) **BARBECUE BASKET**

(71) Applicant: **Dongguan HaoHong Outdoor Products Technology Co., Ltd.**, Dongguan (CN)

(72) Inventor: **Mengwei Yan**, Dongguan (CN)

(73) Assignee: **DONGGUAN HAOSHENG OUTDOOR PRODUCTS TECHNOLOGY CO., LTD.**, Dongguan (CN)

(**) Term: **15 Years**

(21) Appl. No.: **29/768,038**

(22) Filed: **Jan. 27, 2021**

(30) **Foreign Application Priority Data**

Nov. 5, 2020 (CN) 202030667391.9

(51) **LOC (13) Cl.** **07-02**

(52) **U.S. Cl.**

USPC **D7/402; D7/409**
